UNITED STATES PATENT OFFICE.

JOSEPH YOST, OF ASHLAND, PENNSYLVANIA, ASSIGNOR OF ONE-HALF TO CHARLES A. WHIPPLE, OF ASHLAND, PENNSYLVANIA.

ICE-CREAM-CONE SUPPORT.

1,213,055.

Specification of Letters Patent.

Patented Jan. 16, 1917.

Application filed January 18, 1916. Serial No. 72,872.

To all whom it may concern:

Be it known that I, JOSEPH YOST, a citizen of the United States, residing at Ashland, in the county of Schuylkill and State of Pennsylvania, have invented new and useful Improvements in Ice-Cream-Cone Supports, of which the following is a specification.

This invention relates to ice cream cone supports and has for its primary object to provide a device of this character by means of which the cream held within the cone will be protected from coming in contact with foreign bodies, or contaminated air.

An object of the invention is to provide inexpensive means for covering the tops of the cones, said means being effectively held against displacement.

With these and other objects in view the invention consists in the construction, combination and arrangement of parts as will be hereinafter more fully described, illustrated in the accompanying drawing and pointed out in the claim hereunto appended.

Similar reference characters indicate corresponding parts throughout the several views.

In the drawing:—Figure 1 is a sectional view through my invention. Fig. 2 illustrates the cover in blank form.

Referring to the drawing, the numeral 1 designates a plate provided with a series of cone receiving openings 2. The cover 5, the other element of my invention is of substantial rectangular outline with the corner portions cut away as indicated at 6, so that

when one edge is attached to the plate as indicated at 3, side flaps 7 may be bent from the body portion 8 of the cover, so as to cover the said surfaces of the cone and prevent dust laden air from passing from one side to the other side of the group of cones and over the ice cream in the cones.

From the foregoing description taken in connection with the accompanying drawing it will be apparent that I provide a device which is admirably adapted for the purpose of which it is intended, that the device is simple, durable and efficient of construction, and that the device may be manufactured and sold at a comparatively low cost.

Changes in the form, proportion and minor details of construction may be made within the scope of the claim without departing from the spirit or sacrificing any of the advantages of the invention.

What I claim is:—

An ice cream cone support comprising a plate having a series of cone receiving openings, and a sheet of paper of a substantially rectangular outline having one edge portion attached to one edge portion of said plate, there being side flaps depending from said sheet of paper when the latter is folded over the cones.

In testimony whereof I affix my signature in presence of two witnesses.

JOSEPH YOST.
